ZERO SETTING MEANS FOR PLURAL COUNTERS

Original Filed Oct. 27, 1937

UNITED STATES PATENT OFFICE

2,231,288

ZERO SETTING MEANS FOR PLURAL COUNTERS

Alfred Hemmingson, Cambridge, Mass., assignor
to Waltham Watch Company, Waltham, Mass.,
a corporation of Massachusetts

Original application October 27, 1937, Serial No.
171,269. Divided and this application January
20, 1939, Serial No. 252,006

1 Claim. (Cl. 235—144)

This invention relates to counters, including such as have a plurality of counting units, each adapted to be selectively coupled with a driving means for operation independently of the others by one and the same machine. Such counters are used in various situations where a single machine is run under the supervision of two or more operators in rotation and it is desired to register the work of each operator separately over a more or less extended period of time. A counter embodying this invention has been chosen for illustration here which is designed for application to a loom and to add progressively and separately the number of picks of filling woven into the cloth by the loom under control of weavers working in three shifts, from week to week.

The present application is a division of my prior application Serial No. 171,269, filed October 27, 1937, entitled Plural counter, and the phase of the invention herein particularly described and claimed has for its object to provide means whereby all of the counting units may be set to the zero indicating position simultaneously or, alternatively, any one of the units may be set at zero without affecting any of the others.

In the drawing,

Fig. 1 is a front elevation of a plural counter embodying this invention adapted to be set in an upright position in use; the cover of the instrument being broken away sufficiently to show one of the counting units and the selective driving means for all of the units;

Fig. 2 is a cross section taken on a plane designated by the lines 2—2 in Figs. 1 and 4;

Figs. 3 and 4 are detail cross sections of one of the counter units taken on lines 3—3 and 4—4 respectively of Fig. 2, looking in the direction of the arrows applied to said lines;

Fig. 5 is a section taken on line 5—5 of Fig. 1 showing the means by which the counting units may be connected for zero setting in unison or disconnected for individual setting.

Like reference characters designate the same parts wherever they occur in all the figures.

For convenience of description the instrument here shown may be referred to as a three shift pick counter, since it is adapted to count the operations of a loom under the control of three different operators separately. But this designation is not intended, and should not be assumed, to carry any implication of limitations in the scope and utility of the invention. In this embodiment the working parts are contained in a metal box made as a die casting having an integrally united back wall 11 and side walls 12, 13,

14 and 15, and a detachable cover 16 secured in any suitable manner to the side walls. Three counting units are mounted in parallel in the casing. They are all alike and a description of the lowermost one, which is shown in detail in this drawing, will suffice for all.

A series of disks 17, 18, 19, 20, commonly called number wheels, are mounted side by side rotatably on a shaft 21 which in turn is mounted rotatably in bushings 22 and 23 set into the opposite side walls 12 and 14 of the casing. These wheels are of standard character, each having numbers from one to nine and zero on its outer circumference. The right hand wheel, or wheel of lowest order, is rigidly connected to a sleeve 24, and carries on its lefthand side a notched disk 25 and a mutilated gear 26 by which intermittent motion is transmitted to the next wheel through a carrying pinion 27 rotatably mounted on a parallel shaft 28. The pinion 27 meshes with a complete gear 28a secured to a bushing 29 on which the number wheel 18 is rotatable, which gear carries a pawl 30 occupying a recess in the number wheel and adapted to enter any one of ten notches 31 in the surrounding rim of the number wheel. Such pawl and notches constitute a one way clutch by which forward counting movement is imparted to the wheel 18, and which permits said wheel to be independently advanced in the same direction for resetting. Like carrying mechanisms are provided between the wheels 18 and 19 and between the wheels 19 and 20.

A gear 32, rotatable on shaft 21, meshes with a worm 33 on a shaft 34 which rotates in bearings in the end walls 13 and 15 of the casing. A dis- connectable clutch is provided between the sleeve 24 and gear 32, consisting of a sleeve 35 having a notched flange 36 at the end next to the gear, and carrying, in rigid connection with its opposite end portion, a disk 37 having lugs 38 extending through notches in a disk 39 secured non-rotatably to the sleeve 24. The interconnected disks 37 and 39 provide a splined connection between the clutch sleeve 35 and the lowest order number wheel 17. A spring 40 between the sleeve 24 and clutch sleeve 35 presses the latter toward the gear 32 and causes the flange 36 to bear on the face of said gear whenever permitted by a clutch shifter 41. Pins 42 are mounted in the side of gear 32 and are spaced so as to enter the notches in flange 36 when the latter is thus brought up to the gear.

The common drive shaft 34 has two other worms like the worm 33, which are designated 33a and 33b and are suitably spaced to mesh with

the driving gears 32a and 32b (corresponding to the gear 32) of the other two counting units. This shaft is driven from the machine with which the counter is associated by an external shaft 5 43 and a gear train 44, 45, 46, shown in Fig. 1. The clutch shifter 41 previously mentioned is a rod mounted rotatably in the end walls of the casing parallel to the drive shaft, in front of the clutch sleeves 35 and close beside the coupling 10 disks 37 thereof. The rod is cut away in different sides adjacent to the coupling disks 37 of the several units, and each cut away part or notch is of sufficient length to admit the disk when turned toward the latter, and of sufficient depth 15 to permit movement of the disk and clutch sleeve from the position where the flange 36 on such sleeve is clear of the clutch pins 42, to the position where the notches in said flange receive the pins. It is to be understood that the shifter rod 20 is suitably located so that when turned in the manner to bring its unnotched side or surface against the disk 37, the clutch is shifted to, and held in, its disconnected position. The shifter rod is made with so large a diameter that, when 25 thus cut away to the required depth, it still possesses adequate strength and stiffness. The three notches or flats provided in the illustrated embodiment of the shifter, which are distinctively designated in Fig. 1 as 47, 48 and 49, are spaced 30 angularly around the axis of the rod 90° apart from one another, which permits placement of the shifter in four positions of angular rotation, in three of which a selected one only of the three 35 counting units is connected to its driving gear, and in the fourth of which all the units are disconnected. It is thus rotated, and locked in each of the designated positions, by an external knob 50 which is splined to the rod by a set screw 51 occupying a groove 52 in the side of the rod, and 40 has a lug on its end adapted to enter any one of four equiangularly spaced notches 54 on the outside of the casing wall 13. A spring 55 reacting between the rod and knob permits the latter to be disengaged from the notches and causes its 45 lug to snap into any notch with which it is brought into register.

In the particular embodiment of the present invention illustrated in the accompanying drawing, to reset the number wheels at zero the shaft 50 21 is rotated in the same direction that the number wheels are rotated for counting. The shaft of each counting unit has a flattened, or otherwise non-circular extremity 21a located in the bushing 23, to which may be applied the socket 55 portion of a resetting handle. In the side of the shaft may be a longitudinal groove forming a shoulder 56 extending throughout so much of the length of the shaft as is surrounded by the number wheels 18, 19 and 20; or there may be separate 60 notches and shoulders in the same planes with the disks 25 of these several wheels. Each of the disks 25 carries a pawl 57 pivotally seated in a recess in the disk and pressed on by a spring 58 toward the shaft so that it drops in front of 65 the shoulder 56 whenever advanced beyond the shoulder, and also whenever, being beyond the shoulder, the latter is brought up to it. Hence when the shaft is turned forwardly by an applied handle, it picks up the advanced number wheels 70 and brings their corresponding numbers into lateral alinement.

Counters of this character are commonly used to register the work of two or three shifts of operators throughout an entire week, or other convenient working period. At the end of the period

the sums indicated by the several counting units are noted to the credit of the respective operators and the counters set to zero. In order to save time and effort by the supervisor or time keeper who performs this task, it is desirable that all 5 of the units be reset by a single manipulation, instead of two or three successive actions. But it is also desirable at times to be able to set any one of the units to zero without disturbing the others. This may be necessary when one operator 10 is transferred from one machine to another in the middle of the week, while the operators in the other shifts remain. To meet this situation I have provided the counter with means by which the counting units may be coupled together for 15 resetting in unison or disconnected for individual resetting.

The resetting shaft 21 of one of the counting units, preferably the middle one in the case of a three shift counter, may carry a fixed gear 84 and 20 the shafts of the other two units may rotatably support similar gears 84a and 84b respectively. These gears are connected in train by intermediate gears 85a and 85b mounted on studs which project from the casing wall 14. Sliding clutch 25 members 86a and 86b are splined to the shafts of the two outer counting units beside the gears 84a and 84b respectively so as to be movable axially toward and away from these gears, and are formed with notches or holes adapted to receive 30 pins 87 which project axially from the adjacent sides of such gears.

These clutch members may have associated therewith clutch shifters 88a and 88b which, as is shown in Fig. 5, may comprise forked arms 35 mounted on a pivot pin 89 which projects from the back wall of the case, and the branches of such forked arms may lie in circumferential grooves of the clutch members on opposite sides of the axes thereof. The clutch shifters may also 40 have short arms 90a and 90b which may project transversely to the clutch shifters beside one another. A cam 91, secured to a short shaft 92 journaled in the cover, may be located between said short arms, and the latter may be yieldingly 45 held and forced against the cam by a spring 93 connected to their extremities. The cam is symmetrical on opposite sides of its axis and has a throw or rise in each lobe sufficient to disconnect the clutches when turned to the position shown 50 in Fig. 1, and to permit connection of the clutches by the spring when turned so that its low parts are beside the arms 90a and 90b. When the clutches 86a and 86b are disconnected any one of the counting units can be reset independently of the others, and when these clutches are connected the resetting of any unit causes both the others to be reset simultaneously.

The present invention may be embodied in other specific forms without departing from the spirit or essential attributes thereof, and it is therefore desired that the present embodiment be considered in all respects as illustrative and not restrictive, reference being had to the appended claim rather than to the foregoing description to indicate the 65 scope of the invention.

What I claim and desire to secure by Letters Patent is:

A counter comprising two or more counting units each having a rotatable shaft, number indicators rotatably supported on each of said shafts, means for rotating any one of said shafts separately to turn the indicators thereon, gears mounted on the respective shafts, one of said gears being fixed and the others rotatable on 70 75

their respective shafts, intermediate gearing between said gears, a clutch splined to each shaft that carries a rotatably mounted gear and adapted to be moved into and out of driving relation with said gear, a plurality of clutch shifter rods each pivotally mounted at one end and engaging one of said clutches at its other end and having an

arm projecting laterally therefrom, a rotatably mounted cam adapted to engage said arms, and means for maintaining said arms in engagement with said cam whereby said clutch is shifted by movement of said cam.
